BATTERY TERMINAL CONNECTER

Joseph Parmeson, Los Angeles, Calif.

Application November 20, 1935, Serial No. 50,680

7 Claims. (Cl. 173—259)

This invention relates to a battery terminal connecter and more particularly pertains to the connection between an electrical conductor and a binding post on electrical batteries of the type employed in the electrical systems of motor vehicles.

An object of the invention is to provide a connecter of the above character embodying a clamp adapted to be affixed to the end of an electrical conductor and to be detachably clamped into frictional engagement with the binding post or terminal of a battery in which means are provided for protecting the clamp and the post against becoming corroded under the action of acid fumes emanating from the battery around the base of the post.

Another object is to form the connecter clamp so as to obtain the maximum of resiliency therein, whereby connection of the clamp to the binding post and its removal therefrom will be facilitated.

Another object is to provide a construction in the connecter whereby the electrical conductor affixed thereto will be held in an elevated position relative to the top wall of a battery box and whereby application and removal of the clamp is facilitated.

With the foregoing objects in view together with such other objects and advantages as may subsequently appear the invention is carried into effect as illustrated, by way of example, in the accompanying drawing in which:

Fig. 1 is a perspective view of the connecter clamp showing it as detached:

Fig. 2 is a perspective view of a gasket employed in conjunction with the connecter clamp shown in Fig. 1:

Fig. 3 is a view in side elevation of the connecter showing it as applied to the binding post of a battery:

Fig. 4 is a detail in section as seen on the line 4—4 of Fig. 3 with parts in elevation depicting the manner in which the connecter clamp and gasket shown in Figs. 1 and 2 serve to seal the joint between the binding post and the adjacent surface of the top wall of the battery box:

Fig. 5 is a plan view of the connecter showing it as applied.

Fig. 6 is a view of a modified form of the connecter clamp showing it in side elevation with a portion broken away:

Referring to the drawing more specifically A indicates generally the connecter clamp, B designates a binding post of a battery on which the connecter clamp A is designed to be mounted,

and C denotes a gasket designed to be positioned to encircle the base of the post B and to be associated with the clamp A with the gasket interposed between the clamp and the top wall of the battery box at the base of the binding post B.

As here shown the clamp A embodies a substantially U-shaped body portion including an arcuate end member 7 formed to telescopically receive and to encompass the upper end portion of the terminal B. The clamp also embodies a pair of spaced leg members 8 and 9 formed in continuation of the side portions of the arcuate end member 7. A bolt 10 is passed through aligned openings 11 formed in the leg members 8 and 9 in longitudinal slidable engagement with the latter; a head 12 on the bolt bearing against a recessed flat surface 13 on the outer side of the leg member 8 with one edge of the head 12 abutting a shoulder 14 on the leg 8 whereby the bolt will be held against rotation when the head 12 is seated on the recessed surface 13.

A nut 15 is screwed on the threaded end of the bolt 10 to bear against the outer face of the leg 9 as particularly shown in Fig. 5 and when tightened on the bolt 10 serves to clamp the arcuate end portion 7 into tight engagement with the post B.

Formed on the leg 8 and extending in continuation thereof is a ferrule 16 in the form of a split cylinder within which is mounted in a usual fashion the terminal of an electrical conductor 17, by which construction the conductor will extend in continuation of one of the leg members of the clamp.

The binding post B comprises the conventional terminal of the type of storage batteries employed in the electrical systems of motor vehicles, being frusto-conical in form and having an annular flange 18 at the base thereof which seats on the surface of the top wall D of the battery box. The inner periphery of the arcuate end portion 7 of the clamp is tapered to conform to the upper end portion of the binding post B.

Formed on the clamp A and protruding from the under side thereof as shown in Figs. 1, 3, 4 and 5, is a series of spaced prongs 19 which are curved downwardly and outwardly from their intersection with the lower margin of the clamp as particularly shown in Fig. 4. These prongs are designed to serve a two fold purpose, namely to act as spacers to retain the clamp A in an elevated position on the binding post B and in spaced relation to the top wall D of the battery box and at the same time serve to tightly com-

press the gasket C which is interposed between the clamp and the top wall of the battery box.

The gasket C is formed with a circular opening 20 to accommodate the binding post B and is made of felt or similar soft fibrous material which when applied is saturated with an oil, grease or other anti-corrosion substance, and when applied is positioned around the base portion of the binding post to overlie the base flange 18 of the latter as particularly shown in Fig. 4.

The outer margin of the gasket C is formed with a bevel 21 on which the out-turned lower ends of the prongs 19 seat and whereby on pressing the prongs downwardly on the margin of the gasket the latter will be caused to snugly conform to the flange 18 and effect a tight seal of the joint between the binding post and the top wall D of the battery box, and whereby the escape of acid fumes around the juncture of the post and battery box is effectively prevented.

As a means for affording adequate protection against the possibility of acid fumes rising against the under side of the ferrule 16 and the bolt 10, the gasket C is formed with a side elongation 22 to overlie the portion of the surface of the battery box extending beneath the ferrule 16 and bolt 10, as particularly shown in Figs. 3 and 5.

In the application and operation of the invention the saturated gasket C is first positioned around the binding post B to snugly conform to the base portion thereof and to overlie the flange 18. The clamp A is then positioned to encompass the upper portion of the binding post B with the prongs 19 bearing tightly against the marginal portion of the gasket to tightly press the latter in place whereupon the clamp is caused to tightly engage the binding post by tightening the nut 15 on the bolt 10.

The prongs will then also serve to dispose the clamp A in an elevated position relative to the top surface of the battery box thereby supporting the conductor 17 and its engaging ferrule 16 clear of the battery box, and also positioning the clamping nut 15 in such spaced relation to the battery box as to enable its easy adjustment on the bolt 10.

By connecting the conductor 17 to extend in continuation of one of the leg members of the clamp the arcuate member 7 of the clamp will be free to flex throughout its entire length and whereby a maximum of resiliency is afforded which serves to facilitate application and removal of the clamp as compared with the type of U-shaped terminal connection in which the conductor is affixed to the connected portion of the clamp.

In the construction shown in Fig. 6 an apron 23 is formed on the lower margin of the clamp A to serve as a spacer in lieu of the prongs 19, and which apron functions in a fashion similar to that of the prongs in engaging the gasket C and also in spacing the clamp from the battery box.

I claim:

1. A battery terminal connector comprising a clamp having an arcuate end member for encompassing a battery post and formed with leg members extending in continuation of the end portions of the arcuate member, means for attaching an electrical conductor to said clamp, a clamping bolt connecting said leg members, and spacing means protruding downward from the lower margin of said clamp for limiting engage-

ment of the clamp to the upper portion of a battery post.

2. A battery terminal connector comprising a clamp having an arcuate end member for encompassing a battery post and formed with leg members extending in continuation of the end portions of the arcuate member, means for attaching an electrical conductor to said clamp, a clamping bolt connecting said leg members, spacing means protruding downward from the lower margin of said clamp for limiting engagement of the clamp to the upper portion of a battery post, and a gasket encircling the base portion of the battery post engaged by said spacing means for preventing escape of acid around the base of the battery post.

3. A battery terminal connector comprising a substantially U-shaped clamp for engagement with a battery post, said clamp being formed with a series of spaced prongs protruding downward from the lower margin thereof, and means for attaching an electrical conductor to said clamp.

4. A battery terminal connector comprising a substantially U-shaped clamp for engagement with a battery post, said clamp being formed with a series of spaced prongs protruding downward from the lower margin thereof, means for attaching an electrical conductor to said clamp, and a gasket encircling the base portion of the post for sealing the joint around the base of the battery post; said gasket having a margin arranged for engagement by said prongs.

5. A battery terminal connector comprising a substantially U-shaped clamp for engagement with a battery post, said clamp being formed with a series of spaced prongs protruding downward from the lower margin thereof, and means on one end of one of the leg members of said clamp for engaging the terminal of an electrical conductor.

6. A battery terminal connector comprising a substantially U-shaped clamp for engagement with a battery post, said clamp being formed with a series of spaced prongs protruding downward from the lower margin thereof, and means on one end of one of the leg members of said clamp for engaging the terminal of an electrical conductor, and a gasket encircling the base of a battery post to seal the joint around the base of the battery post; said gasket having a margin arranged for engagement by said prongs and formed with an extension to underlie the conductor engaging means.

7. A battery terminal connector comprising a clamp having an arcuate end member for encompassing a battery post and formed with leg members extending in continuation of the end portions of the arcuate member, a clamping bolt connecting said leg portions, means on one end of one of the leg members for engaging the terminal of an electrical conductor, spacing means protruding downward from the lower margin of said clamp for limiting engagement of the clamp to the upper portion of a battery post, and a gasket encircling the base portion of the battery post to seal the joint around the base of the battery post, said gasket having an outer margin arranged for engagement by said spacing means and formed with an extension to underlie the conductor engaging means.
